UNITED STATES PATENT OFFICE.

ALEXANDER FERDINAND VICTOR, OF DAVENPORT, IOWA.

DESIGN FOR A SUPPORTING-FRAME AND CASING FOR STEREOPTICONs.

45,133.

Specification for Design.

Patented Jan. 6, 1914.

Application filed February 3, 1913. Serial No. 746,059. Term of patent 14 years.

To all whom it may concern:

Be it known that I, ALEXANDER FERDINAND VICTOR, a subject of the King of Sweden, residing at Davenport, in the county of Scott and State of Iowa, have invented a new, original, and ornamental Design for a Supporting-Frane and Casing for Stereopticons, of which the following is a full, clear, and exact description, reference being had to the accompanying drawing, forming a part hereof.

My design relates to stereopticons, and its object is to provide a supporting frame for an apparatus of this character that is neat, artistic, and graceful and compact in appearance.

The drawing shows a vertical side elevation of my ornamental design for a supporting-frame and casing for stereopticons.

Referring to the drawing, it will be seen that my design consists of a standard having a circular base-plate and a vertical portion or post arising centrally therefrom, which latter forms a pedestal that supports a bolster whose ends are rectangular and upon which a frame and casing are mounted. This frame and casing comprise a cylindrical-shaped body whose axis is horizontal

and which is of substantially the same diameter throughout its length. This frame and casing extend both forwardly and rearwardly from said pedestal. The wall of the rearwardly extension thereof is perforated and its rear end is closed by a plate having a centrally disposed frustum-conical shaped embossment in the beveled marginal portion of which latter cylindrical holders are mounted. In front of the forward end of said frame and casing a stationary annulus is mounted which is separated from said frame a short distance and supported by upper and lower diametrically opposite longitudinally disposed arms projecting from said frame. This annulus is frustum shaped and is concentric to the axis of the cylindrical frame.

What I claim as new is:

The ornamental design for a supporting-frame and casing for stereopticons, as shown and described.

In witness whereof, I have hereunto set my hand this 30th day of Jan. 1913.

ALEXANDER FERDINAND VICTOR.

Witnesses:

MARGUERITE HASSETT,
S. G. ROSE.
